SPECTACLE FRAME OR THE LIKE

Charles A. Baratelli, Woodstock, Conn., assignor
to American Optical Company, Southbridge,
Mass., a voluntary association of Massachusetts

Application October 18, 1950, Serial No. 12,619

Term of patent 14 years

(Cl. D57—1)

To all whom it may concern:

Be it known that I, Charles A. Baratelli, a citizen of the United States of America, residing at Woodstock, in the county of Windham and State of Connecticut, have invented a new, original, and ornamental Design for a Spectacle Frame or the like, of which the following is a specification, reference being made to the accompanying drawings, forming a part thereof.

Fig. 1 shows a front elevational view of a spectacle frame, showing my new design;

Fig. 2 is a top plan view of Fig. 1, the temples being shown fragmentarily for convenience of illustration; and

Fig. 3 is side elevational view thereof.

The characteristic features of my design are shown in full lines in the drawing.

I claim:

The ornamental design for a spectacle frame or the like, substantially as shown and described.

CHARLES A. BARATELLI.
